UNITED STATES PATENT OFFICE.

WILLIAM STEPHENS, OF MONTESANO, WASHINGTON.

RAKER SAW-GAGE.

SPECIFICATION forming part of Letters Patent No. 756,425, dated April 5, 1904.

Application filed July 14, 1902. Serial No. 115,500. (No model.)

To all whom it may concern:

Be it known that I, WILLIAM STEPHENS, a citizen of the United States, residing at Montesano, in the county of Chehalis and State of Washington, have invented a new and useful 5 Raker Saw-Gage, of which the following is a specification.

This invention is an improvement in implements employed in connection with the filing, 10 gaging, swaging, and jointing of saws; and its object is to enable the teeth to be brought into uniform condition as to length and set.

The invention consists in certain novel features of construction, as hereinafter shown 15 and described, and specified in the claims.

In the drawings illustrative of the invention, Figure 1 is a side elevation of the device applied. Fig. 2 is a top plan view. Fig. 3 is a bottom plan view with the frame in section on 20 the line III III of Fig. 1. Fig. 4 is a view similar to Fig. 1, illustrating a modification in the construction. Fig. 5 is a transverse section on the line V V of Fig. 4, illustrating the manner of employing the device in "jointing" 25 saws.

In this invention is comprised a frame 10 of suitable width and preferably formed with interstices, as shown, to lighten it and with ribs 11 12, extending laterally from one edge, the 30 ribs having a space between their adjacent ends and the frame 10 having a recess in its edge opposite the space between the ribs and affording means for the reception of a slotted gage-plate 13. The plate 13 is secured removably to the plate 10, as by screws 14, the body of the plate being uniform in width with the thickness of the plate 10 and with a projecting portion 15 lying parallel to the body portion 13 and connected thereto at one end only, as 35 shown at 16. Beneath the ribs 11 12 are secured springs 17 18, each rib having its own independent spring, as shown, and attached by their outer ends only to the outer portions of the ribs 11 12, leaving their inner ends free and extending slightly beyond the inner ends of the ribs, as shown. Engaging the ribs 11 12 near their adjacent or inner ends are adjusting-screws 40 19 20, each screw adapted to pass through its respective rib and engage its respective spring- 45 plate 17 18, and thereby adjust them nearer

to or farther away from the plate 13 and its extension 15. Each of the adjusting-screws will be provided, preferably, with a jamb-nut 21 22, as shown, to lock the adjusting-screws in position and also to support the jointing- 55 file, as hereinafter shown. The inner faces of the ribs 11 12 will be some distance above the outer face of the plate 13 and its extension 15, as shown, so that the spring-plates 17 18 may be adjusted a corresponding distance. 60

In the ordinary form of crosscut-saws a certain number of the teeth are arranged as "rakers" or "clearers," and these raker-teeth are arranged at predetermined intervals and shorter than the cutting-teeth and of uniform 65 length, and one of the principal uses to which the present device is appropriated is to assist the filer in cutting off or "swaging" these raker-teeth to a uniform length.

In the drawings a section of a saw of the ordinary form is indicated by dotted lines in position in the implement, 23 representing the body or "back" of the saw, 24 the cutter-teeth, and 25 one of the raker or clearing teeth. The raker-teeth are either filed off to 70 form them shorter than the cutting-teeth or swaged by turning points of the teeth outward, as indicated at 26. The spring 17 is formed with a supplemental stop or transverse notch 75 27 to serve as a gage to guide the filer in swag- 80 ing the raker-teeth, as hereinafter described.

The implement may be employed for the purpose of a gage in cutting off the raker-teeth or as a gage to guide the operator in swaging raker-teeth or as a support for the file 85 when jointing the saw. When employed as a gage to guide the filer in cutting off the raker-teeth, the plate 13 will be employed; but when employed as a guide to the operator in swaging the raker-teeth the plate 13 will be detached, 90 as hereinafter shown.

When employed as a "jointer," the device will be employed, as shown in Fig. 5, with the file (represented at 28) supported by one edge by the jam-nuts 20 21, as shown. When 95 used as a jointer, the frame 10 will be reversed and the rear side placed next the face of the saw, with the file extending over that side and in position to engage the points of the teeth with the frame 10 in contact with the 100

saw and serving as a guide to the file and hold it in proper relations to the saw-teeth.

In using the device with the plate 13 attached the implement is placed in position 5 with the tooth which it is designed shall be a raker-tooth within the cavity between the plate 13 and its extension 15, with the adjacent cutting-teeth on either side engaging the springs 17 18. As before stated, the plate 13 10 and its extension 15 come some distance below the lower line of the springs 17 18, which will cause the points of the tooth which it is designed shall be a raker-tooth to extend above the upper surface of the plate 13. The 15 filer will then file off these projecting ends and move the implement to a position in connection with the next tooth which it is designed shall be a raker-tooth, and so on, thus insuring a perfect uniformity to the raker-teeth.

It will be readily understood that the height of the raker-teeth may be perfectly adjusted by means of the spring-plates 17 18, which are adjustable by the set-screws 19 20.

25 With this simple device the raker-teeth may be formed of exact uniform length and perfectly conforming to and without in any manner effecting the integrity of the cutter-teeth.

The plate 13 and its extension 15 will preferably be of "chilled" iron or hardened steel, so that the file will not affect it and which will indicate to the filer the requisite amount which shall be filed off from the raker-teeth.

The plate 13 is preferably detachable for renewal or repairs and to enable the operator to use the implement without the gage when the raker-teeth are to be swaged instead of filed off.

When employed as a guide to assist the 40 operator in swaging the teeth, the stop 27 comes into action, serving as a stop to the last tooth swaged and coacting with the springs 17 18 to indicate the exact relative lengths of the teeth. In employing the implement for this purpose the springs 17 18 are adjusted 45 to engage the cutter-teeth on opposite sides of the tooth to be swaged. One point is then swaged to the desired height or until it just engages the stop 27 and then the other point 50 of the same tooth swaged until it will engage the stop, when the implement is reversed, and so on throughout the whole length of the saw. By this simple means an implement is produced which may be readily adapted to guide 55 the saw-filer in cutting off or swaging the raker-teeth or in jointing the saw and will greatly facilitate these operations and materially reduce the labor necessary to perform them.

60 With this device the operator by setting a square against the gage can ascertain whether

or not the jointer-file is exactly at right angles with the side of the saw, which position it is necessary for the jointer-file to occupy to insure its proper operation. The operator can 65 also by the same means ascertain whether the ends of the raker-teeth are square or properly swaged, and if they do not "justify" the fault can be detected instantly. By this means the operator is not dependent by sight 70 only to determine the relative position of the raker-teeth or the raker-teeth and the cutter-teeth. This is a great advantage, as one of the prime requisites in filing or swaging the raker-teeth is to have them square or level 75 on their ends or cutting edges.

The device will thus not only be of great advantage to the skilled operator, as by its employment his work will be greatly facilitated, but will also be very convenient to the 80 unskilled operator, as by its use a person without previous knowledge or skill can do as good work as the most skilful operator.

Having thus described my invention, what I claim is—

85 1. A saw-tool comprising a supporting-frame having spaced yieldable plates extending laterally therefrom and stationary at their outer ends and movable at their inner opposing ends, a stationary gage-plate detachably connected to said supporting-frame between said spaced plates and out of alignment with them and adjusting-screws engaging threaded openings in said frame and adapted to depress the movable ends of said spaced plates relative to 90 said gage-plate, substantially as described.

95 2. A saw-tool comprising a supporting-frame having spaced ribs extending therefrom, yieldable plates connected by their outer ends to the outer ends of said ribs and movable 100 by their inner ends, a gage-plate detachably connected to said supporting-frame between said spaced plates and out of alignment therewith, and adjusting-screws engaging threaded openings in said ribs and adapted to depress the 105 movable ends of said spaced plates toward said gage-plate, substantially as described.

110 3. A saw-tool comprising a supporting-frame having spaced yieldable plates rigidly connected thereto by their outer ends and movable at their inner ends, means for adjusting the movable ends of said plates, and a transverse notch extending from the movable end of one of said plates, substantially as described.

115 In testimony that I claim the foregoing as my own I have hereto affixed my signature in the presence of two witnesses.

WILLIAM STEPHENS.
